UNITED STATES PATENT OFFICE.

GILBERT CHRISTIAN, OF DETROIT, MICHIGAN.

CARBURETER.

1,166,112.

Specification of Letters Patent. Patented Dec. 28, 1915.

Application filed March 19, 1914. Serial No. 825,830.

To all whom it may concern:

Be it known that I, GILBERT CHRISTIAN, a citizen of the United States, and a resident of Detroit, in the county of Wayne and State of Michigan, have invented a new and Improved Carbureter, of which the following is a specification.

This invention relates to means for combining air and hydrocarbon vapor to constitute an explosive mixture, suitable for use in internal-combustion engines; and its object is to provide means whereby the amount of explosive mixture delivered to the engine may be quickly varied as desired, 15 to correspond to the speed or load of the engine.

This invention consists, in combination with the outer shell of the mixing or carbureting chamber, and a fuel discharge nozzle 20 consisting of a cylindrical body having a circumferential discharge opening, of a series of small conduits longitudinally of the body for delivering fuel over and above the amount delivered through the circumferential discharge opening, and means for controlling the suction at the discharge ends 25 of these conduits.

It further consists in the novel detail of construction shown, described and particularly pointed out in the claims.

In the drawings, Figure 1 is a central vertical section of my improved carbureter. Fig. 2 is a side elevation showing the operating mechanism for the valve that controls 35 the flow of air through the carbureter. Fig. 3 is an elevation of the fuel discharge nozzle showing the conduits in position thereon. Fig. 4 is a side elevation of a modified form 40 of fuel discharge nozzle. Fig. 5 is a section on line 5—5 of Fig. 4.

Similar reference characters refer to like parts throughout the several views.

In the embodiment shown, the cylindrical shell or body 1 of the mixing chamber has 45 its lower end threaded to receive the lock-nut 2, between which and the mixing chamber the lower wall of the cup-shaped float chamber 3 is clamped. The mixing chamber may be provided with the shoulder 4 by 50 which the cover 5 of the float chamber is held in position; and within the chamber is a float 6 of any approved form for controlling the level of the fuel therein. Leading from the float chamber to a point in the

upper end of the cylindrical shell is a mechanism 55 for supplying a rich mixture such as is desirable when the engine is to be started. This mechanism comprises the outer tube 7 having the air inlets 8 and the fuel inlet 9 therein, the latter being normally submerged and leading into the inner tube 10 which in turn leads, through the medium of the perforated extension 11, into the cylindrical shell 1. A valve 12 and lever 13 control the admission of fuel through this 65 device.

Extending across the lower end of the mixing chamber is a tubular support 15 having passages 16 communicating with the float chamber. A vertical tube 17 passes 70 through said support and has an exteriorly and interiorly threaded central portion 18, a threaded upper portion 28, a threaded lower end 19 and the passages 20 that communicate with the passages 16. An extension 21 has an internal thread to engage the threaded lower end 19 of the tube 17 and hold it in position, its threaded lower end passing through an opening in the tube 22 and being secured thereto by the nut 23. 80 The tube 22 is adapted to convey hot air from any convenient source of supply to the bottom of the carbureter, the flange 24 preferably fitting around the lower end of the body 1.

Threaded upon the outer surface of the tube 17 is a base 26, having a cup-shaped upper surface 27, the portion of the tube 17, opposite the lower part of the cup-shaped surface being removed or hollowed out to 90 form a chamber 29 from which the passages 30 lead laterally through the wall of the tube and outwardly to the periphery of the base. Upon the upper portion 28 of the tube 17, is threaded the collar 31 having the 95 conical upper end 32 and the conical lower end 33, the latter of which may be parallel to and spaced slightly from the cup-shaped surface 27 of the base 26. The collar 31 may be locked in any position of adjustment 100 in respect to the base by means of the screw 34. The tube 17, base 26 and collar 31 constitute the fuel nozzle which has a circumferential discharge opening at the upper edge of the base 26. Connecting to the passages 30 are the upwardly bent pipes 35, one for each passage, that are preferably provided with the beveled upper ends 36

which may terminate at a point somewhat below the lower edge of the conical upper end 32. Engaging with the interior threads on the portion 18 of the tube 17 is a bushing 37 having a calibrated bore.

Sliding within the shell 1 is a tubular throttle valve 38 having the flaring lower end 39 that surrounds the collar 31 and upper ends 36 of the pipes 35, and which, when in the lower position of its adjustment, lies in close relation to the conical upper end of the collar 31, leaving an annular passage into the valve 38 whose interior constitutes the mixing chamber. One side 15 of the cylindrical shell 1 may be provided with the slot 40, through which passes a bolt 41 whose inner end 42 is threaded into the valve 38. The outer end of the bolt passes through a cam slot 43 in the cam 44 20 which is pivoted on the bolt 45 at the upper end of the mixing chamber, and pivotally connected at 46 to the lower end of the cam is an actuating rod 47 that leads to any convenient point. The cam can be disconnected 25 and reversed so that the rod 47 may extend in the opposite direction if desired.

Washers 49 and 50 may be used to prevent leakage between the support 15, the collar 26 and the extension 21.

30 The discharge nozzle shown in Figs. 4 and 5 comprises the vertical tube 17 that is a duplicate of the tube heretofore described. Mounted upon the tube 17 is a base 55 having a cylindrical rim 56 extending upwardly from a flat upper surface 57. This base also has formed therein a series of passages 30 that correspond to the passages 30 in the base 26, and some of these passages (preferably alternate passages) lead to the upwardly bent pipes 35 that are similar to the pipes 35 in Fig. 3, with the exception that as many of these pipes as may be desired are provided with lateral openings 57 extending toward the tube 17. Other passages 30 lead to the shorter tubes 58, whose upper ends terminate at about the level of the rim 56. These passages 30 also communicate with the circumferential groove 59 at the upper surface of the base. Upon the upper portion of this tube 17 is threaded a cylindrical collar 60 having a conical upper end 61 and a flat lower end 62, that is spaced slightly from the upper surface of the base and from the rim 56, to form a circumferential lateral passage for the fuel. This collar has also formed therein a series of small longitudinal passages 63, one for each of the pipes 35 that has an opening 54 therein, each of said passages 63 terminating 55 in the surface of the conical upper end of the collar and in the cylindrical surface of the collar 60, and opposite to and spaced slightly from the opening 57 in the corresponding pipe 35.

60 Operation: In the construction shown in

Figs. 1 to 3, inclusive, fuel from the float chamber will flow through the passages 16, and into the chamber 29, and will stand a little below the upper edge of the base 26; that is, just below the circumferential discharge orifice in the fuel nozzle. When the engine, to which the carburetor is attached, begins to run, the pressure of air within the mixing chamber will be reduced and the liquid fuel will flow out through the circumferential discharge orifice between the base 26 and collar 31. When the throttle valve is raised there is produced, because of the velocity of air along the small tubes 35 and across the ends 36 thereof, a slight suction in these conduits which draws fuel through the passages 30. These two sources will be sufficient to supply the engine under ordinary conditions. When more fuel is required, the throttle valve 38 is raised still 70 more, thereby admitting more air to the mixing chamber and causing a much more rapid flow through the area around the collar 31. This is still further increased in the region of the ends 36 of the conduits 35, 75 which increases correspondingly the suction in the conduits and supplies more fuel to the mixing chamber. It will be seen that this nozzle comprises a circumferential discharge opening 57 and a series of auxiliary 80 discharge openings 36; and that since the lower end of the throttle valve surrounds the auxiliary discharge openings, they are positioned in a passage of less cross-section than that in which the circumferential opening is located, and more subject to suction 85 because of the velocity of the air passing through the carburetor.

90 When the carburetor is equipped with the nozzle shown in Figs. 4 and 5, the operation 95 is as follows:—When the lower end of the throttle 38 practically engages the nozzle at the lower edge of the conical surface 61 of the collar, which occurs at starting or when the engine is running at very low 100 speed, air will be drawn through the passages 63 at a high velocity, which will, in turn, draw fuel from the openings 54 in the pipes 35 across the slight space between the pipes and the collar and into the passages 105 110 115 120 125 130 63 in the collar. Since the velocity of the air near the upper end of the pipes 35 and 58 and the circumferential opening in the nozzle is relatively very low at this time, very little if any fuel will flow therefrom. As the throttle is raised and the speed of the engine increases the velocity of the air around the base 55 also increases and causes fuel to flow in appreciable quantities from the upper ends of the pipes 35 because of this rush of air along these pipes; and as the throttle is raised and the engine attains a still higher velocity, fuel will flow to a considerable extent from the pipes 58. Finally fuel will flow from the circumfer-

ential nozzle formed by the collar 60 and the rim 56, and it is believed that at high speed, fuel will cease to flow through the passages 63.

5 It will be seen that by the use of the pipes 35 and 58 or 35 alone, as the case may be, the outer zone of air passing upwardly between the collar and the mixing chamber receives its proportion of fuel; and that the 10 inner zone is supplied largely from the circumferential discharge opening, especially at the higher speeds of the engine. This causes a better proportioning and a more intimate mixing of air and fuel than would 15 otherwise take place. The collar may be retained in any desired position of adjustment upon the tube 17 by the screw 34. It will be understood that the annular space between the collar 60 and the upper edge 20 of the rim 56 corresponds to the circumferential discharge orifice heretofore referred to as being between the base 26 and collar 31 shown in Fig. 3.

The details and proportions of the device 25 may be changed to conform to the demands of various engines without departing from the spirit of the invention.

I claim:

1. In a carbureter, the combination of a 30 shell inclosing a mixing chamber, a fuel nozzle therein having an annular circumferential discharge opening below its upper end, a second discharge opening above the first discharge opening and spaced apart 35 laterally of the mixing chamber somewhat from the first mentioned discharge opening, a third discharge opening above the second discharge opening, and a throttle valve movable toward and from the discharge openings.

2. In a carbureter, the combination of a shell inclosing a mixing chamber, a fuel nozzle therein having an annular circumferential discharge opening below its upper 45 end, a second discharge opening above the first discharge opening and spaced apart laterally of the mixing chamber somewhat from the first mentioned discharge opening, a third discharge opening above the second 50 discharge opening, said third discharge opening being also spaced apart laterally of the mixing chamber somewhat from the first mentioned discharge opening, and being spaced apart laterally somewhat from the 55 second discharge opening, and a throttle valve movable toward and from the discharge openings.

3. In a carbureter, the combination of a cylindrical body, a fuel nozzle therein having an annular circumferential discharge opening below its upper end, a series of auxiliary discharge openings above the circumferential discharge opening, and a vertically movable cylindrical throttle valve 65 having a flaring lower end inclosing the

nozzle and positioned in close proximity to the auxiliary discharge openings when in its lower position.

4. In a carbureter, the combination of a cylindrical body, a cylindrical fuel nozzle 70 therein, a cylindrical throttle valve surrounding and spaced apart slightly from the nozzle, said throttle valve having a flaring lower end, said nozzle having a discharge opening below its upper end and below the 75 lower end of the throttle valve, and a second discharge opening above the first and having a portion normally above the level of the lower edge of the throttle valve whereby the second discharge opening is located in an area of less cross-section than the first.

5. In a carbureter, the combination of a cylindrical body, a cylindrical feed nozzle therein, a cylindrical throttle valve adjustable from above toward and from the surface of the nozzle, said nozzle having a circumferential discharge opening, and a series of conduits whose open upper ends terminate at a point somewhat above the circumferential discharge opening of the nozzle.

6. In a carbureter, the combination of a cylindrical body, a cylindrical feed nozzle therein, a cylindrical throttle valve adjustable toward and from the surface of the 95 nozzle from above, said nozzle having a circumferential discharge opening, a series of fuel conduits extending vertically along the sides of the nozzle and having open upper ends which terminate at a point somewhat 100 above the circumferential discharge opening of the nozzle.

7. In a carbureter, the combination of a cylindrical body, a fuel receptacle, a tubular support extending across the lower end of 105 the body and communicating with the fuel receptacle, a tube mounted in the support and having holes opening into the interior thereof, a nozzle base mounted on the tube and having a concave upper surface, a collar 110 mounted on the tube above the base and having a convex lower end spaced apart slightly from the concave upper surface of the base to form a circumferential discharge opening, said tube and base having passages to 115 permit fuel to flow into the space between the collar and the base, said base also being provided with a series of laterally extending passages that terminate in vertical extensions whose open upper ends are above the circumferential discharge opening, and a cylindrical throttle valve adjustable toward and from the open ends of vertical exten-

8. In a carbureter, the combination of a 125 cylindrical body, a fuel receptacle, a tubular support extending across the lower end of the body and communicating with the fuel receptacle, a tube mounted in the support and having holes opening into the interior 130

- thereof, a nozzle base mounted on the tube and having a concave upper surface, a collar mounted on the tube above the base and having a convex lower end spaced apart slightly 5 from the concave upper surface of the base to form a circumferential discharge opening, said tube and base having passages to permit fuel to flow into the space between the collar and the base, said base also being 10 provided with a series of laterally extending passages that terminate in vertically extending tubes having beveled open ends, located above the circumferential discharge opening, and a cylindrical throttle valve 15 having a flaring lower end, and means for adjusting the throttle valve toward and from the beveled upper ends of the tubes.
9. In a carbureter, the combination of a mixing chamber, a fuel nozzle therein having an annular circumferential discharge opening below its upper end, a second discharge opening above the first discharge opening, a third discharge opening above the second discharge opening, and a throttle 20 valve movable toward and from the discharge openings.
10. In a carbureter, the combination of a mixing chamber, a fuel nozzle therein, said fuel nozzle having a main body portion provided with a circumferential discharge opening, and also having a series of discharge tubes the upper open ends of which are spaced laterally somewhat from the body portion, said fuel nozzle also being provided 25 with a series of discharge tubes the upper open ends of which are located at a higher level than the ends of the tubes of the first set and are spaced laterally somewhat from the body portion, and a throttle valve movable toward and from the fuel nozzle.
11. In a carbureter, the combination of a mixing chamber, a fuel nozzle therein having a main body portion provided with a circumferential discharge opening, and also having a series of discharge tubes the upper open ends of which are located at one level and spaced apart laterally from the body portion, said nozzle further being provided with a second series of discharge tubes the upper 30 open ends of which are located at a higher level than the ends of the tubes of the first series, and are spaced laterally somewhat from the body portion, said body portion being also provided with a third series of discharge passages the open upper ends of which are at a level above that of the ends of the second series of tubes, and a throttle valve movable into close proximity to the upper ends of the third series of discharge 35 passages.
12. In a carbureter, the combination of a mixing chamber, a fuel nozzle therein having a main body portion provided with a circumferential discharge opening, and also having a series of discharge tubes the open 40 upper ends of which are located at a higher level than the circumferential discharge opening and are spaced slightly from the body portion, some of the tubes having a lateral aperture therein adjacent the main body portion, and the main body portion being provided with a series of passages, one for each apertured tube, the lower end of each of the passages terminating in an aperture adjacent the aperture in the corresponding tube and the upper end leading to an aperture in the body portion at a level above the upper ends of the tubes, and a throttle valve movable into close proximity to the last mentioned apertures.
13. In a carbureter, the combination of a mixing chamber, a fuel nozzle therein having a main body portion provided with a circumferential discharge opening, and also having a series of discharge tubes the open 45 upper ends of which are located at a higher level than the circumferential discharge opening and are spaced slightly from the body portion, some of the tubes having a lateral aperture therein adjacent the main body portion, and the main body portion being provided with a series of passages, one for each apertured tube, the lower end of each of the passages terminating in an aperture adjacent the aperture in the corresponding tube and the upper end leading to an aperture in the body portion at a level above the upper ends of the tubes, the main body portion also having a second series of discharge tubes the open upper ends of which are located below the level of the upper ends of the first series of discharge tubes and are spaced apart somewhat from the body portion, and a throttle valve movable into close proximity to the apertures in the upper end of the body portion.
14. In a carbureter, the combination of a shell inclosing a mixing chamber, a fuel nozzle in the mixing chamber and spaced somewhat from the shell, said nozzle comprising means for discharging fuel into the space between the nozzle and the shell at three levels and at points laterally removed from one another across the space between the nozzle and the shell, said means including as one element an annular circumferential discharge opening.
15. In a carbureter, the combination of a shell inclosing a mixing chamber, a fuel nozzle in the mixing chamber and spaced apart somewhat from the shell, a throttle for restricting the opening between the nozzle and the shell at one level, said fuel nozzle comprising means for discharging fuel into the restricted space between the nozzle and the shell and also comprising means, including an annular circumferential opening for discharging fuel into the relatively unrestricted portion of the mixing chamber at a plurality of levels and at a plurality of

points laterally removed from each other across the space between the nozzle and the shell.

16. In a carbureter, the combination of a tubular body, a fuel nozzle therein, a tubular throttle valve surrounding and spaced apart slightly from the nozzle, said nozzle having a discharge opening below its upper end, and a second discharge opening above the first and having a portion normally above the level of the lower edge of the throttle valve whereby the second discharge opening is located in an area of less cross-section than the first.

17. In a carbureter, the combination of a tubular body, a feed nozzle therein, a tubular throttle valve adjustable from above toward and from the surface of the nozzle, said nozzle having a circumferential discharge opening, and a series of conduits whose upper ends terminate at a point somewhat above the circumferential discharge opening of the nozzle.

18. In a carbureter, the combination of a body, a fuel receptacle, a tubular support extending across the lower end of the body and communicating with the fuel receptacle, a tube mounted in the support and having holes opening into the interior thereof, a nozzle base mounted on the tube and having a concave upper surface, a collar mounted on the tube above the base and having a convex lower end spaced apart slightly from the concave upper surface of the base to form a circumferential discharge opening, said tube and base having passages to permit fuel to flow into the space between the collar and the base, said base also being provided with a series of laterally extending passages that terminate in vertical extensions whose open upper ends are above the circumferential discharge opening, and a cylindrical throttle valve adjustable to-

ward and from the open ends of the vertical extensions.

19. In a carbureter, the combination of a tubular body, a fuel nozzle therein, a tubular throttle valve adjustable from above toward and from the surface of the nozzle, manually operable means for adjusting said valve toward and from the surface of said nozzle, said nozzle having an annular circumferential discharge opening, and a conduit whose open upper end terminates at a point somewhat above the annular circumferential discharge opening in the nozzle.

20. In a carbureter, the combination of a tubular body, a fuel nozzle therein, a tubular throttle valve adjustable toward and from the surface of the nozzle, manually operable means for adjusting said valve toward and from the surface of said nozzle, said nozzle having an annular circumferential discharge opening, and a conduit whose open end terminates at a point the elevation of which is different from that of the annular circumferential discharge opening.

21. In a carbureter, the combination of a tubular body, a fuel nozzle therein, a tubular throttle valve having a flaring end between which and the nozzle a relatively restricted passage way is formed, manually operable means for adjusting the throttle valve in respect to the body, said fuel nozzle having an annular circumferential discharge opening, means for discharging fuel into the relatively restricted passage way at an elevation different from that of the annular circumferential discharge opening.

In testimony whereof I have signed this specification in the presence of two subscribing witnesses.

GILBERT CHRISTIAN.
